UNITED STATES PATENT OFFICE.

WILLIAM JOSEPH TONER AND JAMES JOHN TONER, OF SOUTH KENSINGTON, ENGLAND.

SOAP-BOX FOR SHAVING PURPOSES.

1,379,885.

Specification of Letters Patent. Patented May 31, 1921.

Application filed August 10, 1920. Serial No. 402,655.

To all whom it may concern:

Be it known that we, WILLIAM JOSEPH TONER and JAMES JOHN TONER, subjects of the King of Great Britain, residing at, respectively, 95 and 62 Finborough road, South Kensington, in the county of London, in England, have invented new and useful Improvements in or Relating to Soap-Boxes for Shaving Purposes, of which the following is a specification.

The invention relates to metallic soap boxes having a ring to hold the soap tablet which fits into a cup, the said ring being provided with a cover fitted to it by a bayonet slot connection.

In the accompanying drawings, Figure 1, is a plan of the top of the box; Fig. 2, is a front elevation of the box; Fig. 3, is a sectional elevation of Fig. 2; Fig. 4, is a plan 20 of the top of the ring, and Fig. 5, is a plan of the bottom of the ring.

Our invention is constructed with a metallic tapered ring *b*, having a bead *d*, and a turned under or beveled edge *e*, at 25 the bottom as shown in Fig. 3, this said ring *b*, holds or supports the soap tablet *f* of the shape shown in Fig. 3. At the top portion *j* of the tapered ring *b* we provide stamped projections *i* for engaging with 30 the bayonet or T-shape slots *h*, formed in

the cover *c* as shown in Figs. 1, 2, and 4, the said cover is provided with a bead *k*, and locked or unlocked to or from the top portion of the tapered ring *b*. A cup *a* is provided of a tapered formation in order 35 to receive the tapered ring *b* as shown in Fig. 3.

When the soap tablet *f* is required for use, the cup *a* is removed from the tapered ring *b*, and by means of an ordinary shaving brush the soap is operated on at the bottom *g*. Directly the soap tablet has been worked out a new soap tablet may be inserted at the top of the tapered ring *b*, this 40 operation can be repeated when necessary. 45

The cup *a* tapered ring *b* and cover *c* are made of metallic substance.

We claim:

A soap box for shaving purposes having a tapered ring with a bead at the top and a 50 beveled edge at the bottom, and two projections at the top, a tapered cup and a cover with two bayonet slots to engage with the projections at the top of the tapered ring, the said ring to support a special 55 shaped soap tablet, substantially as described and shown on the accompanying drawings.

WILLIAM JOSEPH TONER.
JAMES JOHN TONER.
